UNITED STATES PATENT OFFICE.

ABRAHAM BOTKIN, OF HYATTSVILLE, MARYLAND.

VEST BELT.

Application filed April 3, 1923. Serial No. 629,650.

To all whom it may concern:

Be it known that I, ABRAHAM BOTKIN, a citizen of the United States, residing at Hyattsville, Maryland, have invented new and useful Improvements in Vest Belts, of which the following is a specification.

This invention relates to vest-belts, and more particularly to a vest which is of such construction that it may be used with a maximum degree of comfort without sacrificing its attractive appearance.

One of the objects of this invention is to construct such a vest which will provide ample pockets for receiving money, papers, etc.

Another object of this invention is to provide such a vest which will replace the use of belts or suspenders, etc.

Further and still other objects of this invention will appear from the more detailed description set forth below wherein there is represented by way of illustration, in Fig. 1 of the drawing, a vest-belt constructed in accordance with this invention; in Fig. 2, a detail partly in section of such a belt showing concealed pockets; in Fig. 3, a section on line 3—3 of Fig. 2; and in Fig. 4, a section on line 4—4 of Fig. 1.

As set forth more particularly by way of example in these figures, there is shown a belt 1, made preferably double with two contiguous band members, attached along their upper edges, so that there is a front side 2, and a rear side 3. The belt is preferably made from a single piece of material as illustrated and folded over so as to produce two side or band members, a front and a back one, contiguous to each other although it might be made of two separate portions stitched together along the edge 4. The contiguous band members obviously have a space between them. Conventionally, there are shown buttons 5, with corresponding button holes 6, for fastening the vest-belt in position. In this way there is obtained a belt open along its lower edge to provide a space within which secret or concealed pockets may be placed.

Inasmuch as this belt is designed to replace a vest, pockets 7 and 8 are provided with their openings 9 and 10, respectively available from the outside. In addition to these pockets there are also provided in the preferred form, additional pockets 11 and 12 which in their normal position are inverted and lie between the sides 2 and 3

of the belt and within it in a concealed position. These pockets 11 and 12 are formed in the usual way and are stitched to the side 3 of the belt as shown at 13. This stitching 60 forms a joint about which the pocket may be swung into its operative or into its closed positions. This comes about because as just pointed out these concealed pockets stitched as shown at 13 may be swung up into the 65 space between the band members or sides 2 and 3 when they are to remain concealed; whereas when it is desired to use them they may be swung from within this space so that their contents may be reached. Inasmuch as these pockets 11 and 12 will usually lie inverted, they are preferably provided with flaps 14 and 15 and buttons 16 and 17 respectively, to keep them closed and to prevent their contents from falling out. 70 While the construction described is the preferred form, the flaps 14 and 15 may obviously be omitted, and buttons 16 and 17 used with button holes formed in the outer faces of the pockets themselves. 75

To assist the vest-belt in performing obviously desirable functions, other features are also preferably provided. For example, belt straps 18, 18 are shown within which a belt 19 for supporting trousers may be inserted. When so used, the belt straps on the trousers will be inserted about the belt 19 and these belt straps, will fall somewhere in between the belt straps 18, 18, the latter being spaced apart for this purpose. 80 Among still other features are shown two sets of straps or tabs, numbered 20, 20 and 21, 21, respectively. The tabs 20, 20 are used to take the place of suspenders and are therefore preferably six in number, spaced 85 apart at intervals corresponding to the conventional suspender buttons on the trousers, these tabs 20, 20 being provided with button holes 22, 22 to receive the suspender buttons just referred to. The tabs or straps 21, 100 21 are similar to the tabs 20, 20 and are provided with button holes 23, 23, but are usually only two in number, since they are designed to receive the loops of undergarments such as drawers. In use, such loops 105 are passed over the tabs 21, 21, and then these tabs are buttoned to buttons sewed or otherwise attached to the belt, adjacent to the button holes 23, 23.

In its preferred form, there are also provided stiffening members 24, 24 to assist in 110 preserving the shape of the belt.

From the more detailed description given above, it will be obvious to those skilled in the art, to make changes in form, design, or other details without departing from the spirit or the scope of the invention set forth.

Having thus set forth my invention I claim:

A vest belt comprising a plurality of band members secured together in superposed relation, and free from each other at a longitudinal edge, pockets between said members, each pocket secured to a free edge of one

only of said members.

ABRAHAM BOTKIN.
